UNITED STATES PATENT OFFICE

2,110,340

ALARM DEVICE

Frank Riley, Jr., Houston, Tex., assignor to Miller
Fuel Engineering Company, Houston, Tex., a
corporation of Texas

Application August 17, 1936, Serial No. 96,431

1 Claim. (Cl. 116—102)

This invention relates to an alarm device.

An object of the invention is to provide a device of the character described specially designed to be attached to a boiler, and arranged to be actuated when the level of the water in the boiler is below a predetermined level; it being the purpose of the invention to give warning to the attendant that the water in the boiler is too low.

It is another object of the invention to provide an alarm device equipped with trip means arranged to be released by the influence of the steam in the boiler when the water reaches a predetermined level with an actuating device arranged to be rendered operative upon release of the trip means, and to thereupon actuate the alarm.

With the above and other objects in view, the invention has particular relation to certain novel features of construction, operation and arrangement of parts, an example of which is given in this specification and illustrated in the accompanying drawing, wherein:

Figure 1 shows a side view of the apparatus attached to the boiler, and

Figure 2 shows a sectional view thereof taken on the line 2—2 of Figure 1.

Referring now more particularly to the drawing wherein like numerals of reference designate similar parts in each of the figures, the numeral 1 designates the boiler. There is a T-connection 2 which is connected into the boiler below the normal water level by means of the tubular nipple 3, and connected into and upstanding from the corresponding end of the T-connection 2, there is a tubular nipple 4 which is normally closed by a conventional valve 5 and on which, above the valve, there is mounted the conventional steam whistle 6. The valve 5 may be opened by the valve actuating lever 7 which is pivotally mounted thereon in the usual way. A chain 8 is attached at one end to the free end of the lever 7 and said chain is connected at its other end to the weight 9. This weight has a bail 10 to receive the supporting lever 11. This lever is pivoted at one end to the lower end of the T-connection 2 and its other end is engaged by the depending pivotally mounted latch 12 whereby the weight is normally held in inactive position.

Upstanding from the other end of the T-connection 2, there is an elongated tube 13 whose upper end is closed by the cap 14. The cap 14 has a laterally extended lug 15 to which the upper end of the release rod 16 is connected.

The upper end of the latch is pivoted to a laterally extended lug 17 carried by the T-connection 2, and the lower end of the release rod 16 is piv-

otally connected to the latch out beyond its pivotal connection with the lug 17.

There is a steam pipe 18 extended axially through the nipple 3 and whose outer end is upturned and connected into the lower end of the 5 nipple 4. The inner end of this steam pipe 18 is also upwardly curved so that its inlet end will be above the corresponding end of the nipple 3.

So long as the level of the water in the boiler is above the nipple 3, dry steam will be excluded 10 from the tube 13 and said tube will not be thereby expanded in length sufficient to trip the latch 12. However, as soon as the water level descends sufficiently to admit steam into the nipple 3, said steam will pass also into the tube 13 and will 15 heat and expand said tube, causing an upward pull on the rod 16. This upward pull will actuate the latch 12 outwardly, releasing the free end of the lever 11 permitting the weight 9 to drop, thus opening the valve 5. The inner end of the 20 steam pipe 18 being upturned, only dry steam will be admitted to the whistle 6 and when the valve is opened, an alarm will be given, indicating the low level of the water in the boiler. The inner end of the steam pipe 18 being upturned will prevent the discharge of water through the whistle 6, 25 but will permit dry steam only to reach said whistle.

The drawing and description disclose what is now considered to be a preferred form of the invention, by way of illustration only, while the broad principle of the invention will be defined by the appended claim.

What I claim is:

A device of the character described comprising 35 a T-shaped tubular support mounted on the side of and adapted to be connected into a boiler, a steam whistle on one arm of said T-shaped tubular support, a steam pipe extended horizontally through the support into the boiler and arranged 40 to supply steam to the whistle, said steam pipe having the end thereof which is in the boiler upturned, a normally closed valve controlling the supply of steam from the steam pipe to the whistle, a weight fastened on the lower end of 45 said T-shaped support, releasable means normally holding the weight inactive, means connecting the weight with the valve, means mounted on the other arm of said support, arranged to be actuated by the steam from the boiler when the water 50 in the boiler reaches a predetermined low level and effective to release the weight suspending means whereby the weight is rendered active to open the valve to permit the discharge of steam through said steam pipe. 55
